UNITED STATES PATENT OFFICE.

DAVID NICKEL, OF MORRIS, ILLINOIS.

DESIGN FOR A CASTER-PIN.

SPECIFICATION forming part of Design No. 26,733, dated March 9, 1897.

Application filed December 17, 1896. Serial No. 616,072. Term of patent 7 years.

To all whom it may concern:

Be it known that I, DAVID NICKEL, a citizen of the United States of America, residing at Morris, in the county of Grundy and State of Illinois, have invented a certain new and original Design for a Caster-Pin, of which the following is a specification, reference being had to the accompanying drawings, in which—

Figure 1 is a side view of my caster-pin design. Fig. 2 is a cross-section in line 2 2, Fig. 1; and Fig. 3 is a similar section in line 3 3, Fig. 1.

The leading features of my design consist in a cylindrical body having a portion of its length squared and formed with oppositely-extending wings at the squared portion.

In the drawings, A represents the stem or cylindrical portion of the caster-pin, a the head, and a' the pointed end. At B B' the stem is squared (see Fig. 2)—that is to say,

in side elevation four longitudinally-extending plane surfaces are formed at each place, which in cross-section form a square inscribed within the periphery of the stem. Two pairs of radially-extending wings b b' are formed at two opposite corners of the squared portions, these wings having curved outlines which merge into the surface of the stem at their ends.

The essential features of my design I consider the laterally-extending wings and the adjacent squared portions.

I claim as new and desire to secure by Letters Patent—

The design for a caster-pin; substantially as shown and described.

DAVID NICKEL.
